UNITED STATES PATENT OFFICE.

JOHN DIX MORGAN, OF NEW YORK, N. Y.

APPARATUS FOR THE PRODUCTION OF CYANOGEN COMPOUNDS.

1,309,650.

Specification of Letters Patent. Patented July 15, 1919.

Application filed June 30, 1917. Serial No. 177,863.

To all whom it may concern:

Be it known that I, JOHN DIX MORGAN, a citizen of the United States, and a resident of New York city, in the county of New York and State of New York, have invented certain new and useful Apparatus for the Production of Cyanogen Compounds, of which the following is a specification.

My invention relates to that class wherein 10 the apparatus is adapted for the practice of a process for the production of cyanogen compounds by the fixing of nitrogen with carbon and an alkali metal.

Among other objects of my invention is to 15 provide means whereby a continuous supply of the solid materials required for the chemical reaction can be delivered into a suitable furnace or chamber and a like supply of nitrogen and heat may be delivered therein 20 and for governing the temperature of such chamber so that the necessary chemical reactions shall continue without intermission, as long as the supply of material, nitrogen, and required heat is continuous; also to provide 25 vide means for treating finely comminuted material when so delivered into such chamber in a diffused mass, as well as treating such material when in fragments or briquets; also to provide means for causing the diffused 30 particles to contact with and adhere to the inner wall of the chamber and for slicing, cutting or scraping therefrom the accumulations or coatings so gathered on the walls at appropriate intervals and for receiving them 35 in a portable receptacle at the bottom of the chamber and for removing them therefrom while yet in a plastic mass without in any way interrupting the continuous operation of the apparatus. Also to so shorten the 40 time required for effecting the necessary reaction on a given amount of material that there may be a continuous delivery of the latter to the reduction chamber.

In my copending application for a process 45 for producing cyanogen compounds filed contemporaneously with this, and bearing Serial No. 177,863, I fully set forth the state of the art and hence do not need to repeat such statement in the present application 50 which is for an apparatus adapted for the practice of such process, it being obvious to one skilled in the art that the time element required for the absorption of nitrogen by a porous mass of the solid material is 55 dependent upon the bulk of the mass and the pressure of the gas; also that with the mate-

rial finely comminuted the surface exposed for immediate contact with the nitrogen molecules is proportionately increased and the time required for effecting the reaction 60 correspondingly diminished. Heretofore as recited by me in the statement of the art referred to there has been great difficulty encountered in handling the treated material through the latter becoming plastic and viscid as a result of the rise in temperature in 65 the heated zone and adhering to the retort where it comes in contact therewith. Heretofore no apparatus has been adapted for the segregation and removal from the retort 70 of such treated material while yet heated and in a plastic condition, such apparatus as now designed either being adapted for the cooling of the charge before its removal or for the removal of the material by means 75 of screw conveyers or the like from the heated zone to a receptacle at normal temperature with the result that the material becomes chilled in the course of transfer and adheres to the conveyer choking the conduit and requiring removal with a hammer 80 and chisel. Hence in a continuous feed retort its commercial utility is dependent on the ability to successfully collect and remove the plastic material as the same accumulates without clogging or choking the retort 85 or impeding or interrupting the reactions progressing within the heated zone of the chamber.

Having thus generally stated some of the 90 objects of my invention I will more particularly describe the same by reference to the drawings in which similar reference characters refer to identical parts.

In the drawing, Figure 1 shows a sectional elevation of my apparatus cut through the center, Fig. 2, is a detail of the reamer M, and Fig. 3, is a diagrammatic front view of a section of the apparatus, wherein the jacket E', is shown as inclosing a plurality 100 of stacks.

The vertical casing, or stack B, is shown mounted on a raised base R, supported on four legs r', two of which are shown, thus providing for the utilization of the bottom 105 of the furnace for the discharge of treated material. The furnace or chamber A, is provided with a jacket E', as shown, forming a heating chamber E, to which a non-oxidizing preheated gas, as carbon monoxide, may 110 be supplied through the pipe N, and the inlets n, controlled by the valves n'.

In the commercial practice of my invention a multiplicity of stacks will frequently be required in a single plant and in such case I inclose all of them in a single jacket E', 5 in order to effect an economy in heat insulation and in Fig. 3, I illustrate this construction as applied to a plurality of stacks.

The inlet c, for the solid material is located near the top of the chamber and connected therewith are the means for a continuous governed supply of material shown as the hopper C, the bottom of which opens into the conduit c', in which is mounted the screw conveyer C'. The conduit c', is enclosed in a water jacket D', and water circulation is provided by the inlet pipe d, controlled by the valve d', and outlet d', controlled by the valve d'. The upper part of the stack B, is also provided with a water jacket D, having an inlet d⁶, controlled by the valve d⁷, and an outlet d⁴, controlled by the valve d⁵. The gaseous material is supplied through the pipe G, controlled by the valves g, and g², and the inlet G', preferably in the lower part of the stack, but the location may be varied as desired. Means are provided by the removable plug g', for cleaning the inlet in event that the same should become clogged by adhesive material, 30 a bypass g³, controlled by the valve g⁴, is provided for admitting nitrogen to the heating jacket E', as an alternative means of preheating the same. An outlet K, for flue gases, is controlled by the valve K'. L, is the flue from the heating chamber E, and is controlled by the valve L'. The reamer M, is mounted on the arms m, which are brought to the center and connected to the end of a sinker bar or stem m', as shown in the detail Fig. 2. The stem m', projects through the opening in the top of the stack B, when the reamer is in use, and is operatively related to a cable, pulley and drum, not shown, for the lowering and raising of 40 the reamer. The lower edge of the reamer M, is beveled at such an angle as to form a suitable cutting blade. Means for sealing the chamber to receive gas under pressure are shown by the valve K', already described, the gate valve O, at the top of the stack B, and the valve P, at the lower end of the hopper C. The bottom of the chamber A, is closed by the gate valves H, and H'. The intervening section A³, is preferably made with a larger diameter in which case the valve H', is enlarged to correspond. The bottom is elevated to permit of a car J, being placed thereunder to receive the treated material.

60 The operation of the apparatus is as follows:

To start the furnace the inlet valves n', of the supply pipe N, are opened. The gate valve O, at the top and the gate valves H, and H', at the bottom of the chamber A,

are closed. The inlet and outlet valves d' and d⁶ of the water jacket D are opened to secure a circulation of water therein and thus reduce the temperature of the section or zone of the chamber A controlled thereby. 70 The valves g and g², of the nitrogen supply pipe G are opened and a supply of preheated nitrogen is admitted. The flue valves L' and K' are opened and the section or zone of the chamber A controlled by the heating jacket 75 E is raised to a temperature suitable for effecting a reaction between the active materials supplied to the chamber which temperature, with a catalytic agent present, is about 1000° C., then the screw conveyer C', is started and the operation of the apparatus proceeds until it is desired to remove the accumulated material from the wall when the screw conveyer C', is stopped and the chamber A, is sealed by closing the flue valve K', 80 and gate valve P, and the gas is admitted under a slight pressure to expedite the completion of treatment of the coatings on the wall and material on the bottom of the chamber. After from 1 to 5 minutes the valves last named are opened and pressure reduced to normal on the gas supply, the gate valve O is then opened and the reamer M, is operatively lowered to the bottom of the chamber slicing and scraping the coating of adhesive material from the wall and delivering it at the bottom of the chamber. The reamer is then removed from the stack and the gate valve O closed. The valve H, is opened and the treated material is permitted 90 to descend to section A³, of the chamber, when the valve H, is closed and the valve H', is opened and the content of the treated material is dumped into a receptacle as J. If the radiation from section A³, of the 100 chamber unduly lowers the temperature therein, the valve H, may be partially opened to supply heat thereto before discharging treated material.

While the apparatus may thus be functioned for the practice of a continuous process as described, it is equally adapted to function for an intermittent feed if it be desired to alternately coat the wall of the chamber and then supply nitrogen under 115 pressure for absorption by the coating, thus building up the treated material in layers. The operation may be varied by feeding material in with the nitrogen supply cut off thus effecting the delivery by gravity of a 120 substantial amount of the material to the bottom of the chamber in a porous bulk and of then supplying nitrogen under pressure and of absorption of the latter the removal of the treated material and a recharging of 125 the chamber.

I do not limit in any way the method of operation of the furnace the same being limited only by its functional capacity.

Having thus specified, shown and de- 130

scribed the same, I claim as novel and my invention:

1. In an apparatus for producing cyanogen compounds, in combination, a substantially vertical casing, a chamber therein having an extended longitudinal section and a cross section so limited as to adapt the inner wall for engaging adhesive material therewith, means for intermittently slicing the wall and for removing solid material from the heated chamber, means for maintaining a heated zone in said chamber comprising a heating jacket inclosing such zone section and provided with pipe and valve connections for supplying preheated gas thereto, inlets for the solid and gaseous material and an exhaust flue.
2. In an apparatus for producing cyanogen compounds, in combination, a substantially vertical, tubular casing, a chamber therein having an extended longitudinal section and a cross section so limited as to adapt the inner wall for engaging adhesive material therewith, means for intermittently slicing the wall, valves at the bottom of the chamber adapted for the removal of solid material, inlets for solid and gaseous material and an exhaust flue.
3. In an apparatus for producing cyanogen compounds, in combination, a substantially vertical tubular casing, a chamber therein having an extended longitudinal section and a cross section so limited as to adapt the inner wall for engaging adhesive material therewith, a gate valve at the upper end of the chamber suitable for permitting the passage of a reamer, having a cutting edge adapted to slice the chamber wall, mounted to be operatively lowered to the bottom of the chamber and withdrawn therefrom, means for a continuous supply of gaseous and solid material, means for removing solid material from the heated chamber and means for heating a zone in said chamber and for exhausting the waste gases therefrom.
4. In an apparatus for producing cyanogen compounds, in combination, a substantially vertical casing, a chamber therein having an extended longitudinal section and a limited cross section, means for maintaining a low temperature zone in the upper

part thereof and a heated zone in a lower section thereof, an inlet for solid material in said low temperature zone an outlet for the same below the heated zone, an inlet for gaseous material and an exhaust flue.

5. In an apparatus for producing cyanogen compounds, in combination, a substantially vertical, tubular casing, a chamber therein having an extended vertical section, means for maintaining a low temperature zone in the upper end of said chamber, comprising a water jacket inclosing the same and valve controlled inlet and outlet pipes for circulating water in such jacket, an inlet for solid material in said low temperature zone, means for maintaining a heated zone in a lower section thereof, means for slicing the wall of the chamber, an inlet for gaseous material and an exhaust flue.

6. In a furnace for producing cyanogen compounds, in combination, a chamber, an inlet thereto for solid material, opening from a water-jacketed conduit, a water jacket inclosing such chamber for a section below such inlet, adapted to maintain a low temperature zone at and near the inlet for the material, means for supplying heat to the chamber, an inlet for gaseous material and separate outlets for the treated material and waste gases.

7. In an apparatus for producing cyanogen compounds, in combination, a tubular vertical chamber, adapted by its contour and relative dimensions to engage the plastic material on its inner wall, a valve at the upper end of the chamber adapted to admit a reamer into the chamber, a circular reamer, beveled at its lower end to form a cutting edge, mounted to descend into the chamber, at intervals, to slice the accumulation of coated material from the inner wall and valves at the lower end of the chamber to permit of the removal of treated material while in a plastic state.

Signed at New York in the county of New York and State of New York this seventh day of December A. D. 1916.

JOHN DIX MORGAN.
